(57) CLAIM

The ornamental design for overalls as shown and described.

DESCRIPTION

FIG. 1 is a front view of overalls showing the new design; FIG. 2 is a front view of the overalls of FIG. 1, in which a waistband of the overalls is unfastened;

FIG. 3 is a rear view of the overalls of FIG. 2;

FIG. 4 is an enlarged detail view of a bib portion of the overalls taken from line 4 in FIG. 2; and,

FIG. 5 is an enlarged detail view of the opposite side of the bib portion of the overalls shown in FIG. 4.

The lighter and darker shading applied to the surfaces of the overalls represent a contrast in appearance. The portions of the overalls defined by either long dashed broken lines or short dashed broken lines depict portions of the overalls that form no part of the claimed design. The dash-dot broken lines define the bounds of the enlarged detailed views and form no part of the claimed design.
